UNITED STATES PATENT OFFICE.

RODOLPHE W. E. CHRISTESEN, OF NEW BRITAIN, CONNECTICUT, ASSIGNOR TO
THE RUSSELL & ERWIN MANUFACTURING COMPANY, OF SAME PLACE.

DESIGN FOR A LOCK-CASE.

SPECIFICATION forming part of Design No. 20,099, dated August 12, 1890.

Application filed June 23, 1890. Serial No. 356,496. Term of patent 14 years.

To all whom it may concern:

Be it known that I, RODOLPHE W. E. CHRISTESEN, a citizen of the United States, residing at New Britain, in the county of Hartford and State of Connecticut, have invented and produced a new and original Design for a Lock-Case, of which the following is a specification, reference being had to the accompanying drawings, forming part thereof.

10 Figure 1 is a perspective view showing my design for a lock-case, and Fig. 2 is a like view of the keeper for said case.

15 The leading feature of my design consists in the raised scroll figures and leaflets in the surface ornamentation of the front of the case and keeper and in the contour or outline of the central portion and wings at the upper and lower edges.

20 A is the central portion of the case, and B the central portion of the keeper. The central portion of the case is of rectangular form in outline, and at the top and bottom edges there are ornamental wings C, the outlines of which are composed of curved and straight 25 lines in the form shown, forming what may be termed "conventional leaves." The surface at the central portion of each wing is ornamented by rosettes 3. The surface ornamentation for the front of the central portion A consists of a circular figure 4 in the center, from which two pairs of scroll ornaments 5 5 5 extend, with leaflets 6 at the inner end of each scroll and a leaflet 7 on each side between each pair of scrolls. The design for the keeper is 35 analogous to and in harmony with the design for the lock-case, the central portion B being

of a rectangular outline, while wings D D at the upper and lower edges are bounded by straight and curved lines and forming conventional leaves. The surface ornamentation 40 for the central portion B of the keeper consists of four curved figures 8 8 8, (the upper and lower figures being in the form of scrolls, while the two middle figures represent parts of scrolls,) connected together with leaflets 9 45 9 at their junction, as shown.

What I claim is—

1. The design for a lock-case herein shown and described, the same comprising the central portion of rectangular outline, the upper 50 and lower wings having an outline composed of straight and curved lines, the central figure, scrolls, and leaflets on the front of the central portion, and rosettes on the wings, as set forth.

55 2. In a design for a lock-case herein shown and described, the central portion of the case having a rectangular outline with surface ornamentation, and the upper and lower wings having an outline in the form of conventional leaves at the upper and lower edges of said central portion, as set forth.

3. In a design for a lock-case herein shown and described, the central portion with rectangular outline having the centrally-set circular figure 4, two pairs of scrolls 5 5 5, with leaflets 6 at their inner end, and the leaflet 7 between each pair, as set forth.

RODOLPHE W. E. CHRISTESEN.
